John J. Finan
ATTORNEY

UNITED STATES PATENT OFFICE

KARL KRUENING, OF JAMAICA, NEW YORK

GOOGLES

Application filed September 20, 1927, Serial No. 220,659. Renewed April 15, 1930.

This invention relates to goggles. Among the objects of the invention is the provision of goggles for the use of aviators, racing drivers, and other like purposes, wherein the lenses may readily be inserted and replaced, which will afford a maximum range of vision, which may be fitted to the face of the wearer with accuracy and comfort, and which shall be practical and efficient to a high degree in use.

A further object of the invention is the provision, in connection with goggles of the type described, of means whereby the lenses of the goggles may readily be replaced without subjecting the frames of the goggles to any undue strain or without rendering it necessary for the person making the change to use the awkward procedure now necessary.

The invention accordingly consists in the features of construction, combinations of elements, the arrangement of parts which will be exemplified in the construction herein-after described, and of which the scope of application will be indicated in the following claims.

In the accompanying drawing, in which is shown one of the various possible illustrative embodiments of this invention:

Fig. 1 is a plan view of the front side of the improved goggles, as assembled for use, the rubber cushion therefor being shown in place.

Fig. 2 is a vertical sectional view taken on line 2—2 of Fig. 1 illustrating the manner in which the goggles are associated with the face, particularly the eyes, of the wearer.

Fig. 3 is an elevational view of an edge portion of the goggles showing an improved hinge construction therefor.

Fig. 4 is an enlarged partial plan view of the hinge construction, a portion being broken away as on line 4—4 of Fig. 3 to show the manner of assembly.

Fig. 5 is a vertical sectional view taken on line 5—5 of Fig. 1 of the means for holding the lens retainer in place.

Fig. 6 is a similar vertical sectional view showing a modified means for holding the lens retainer in place.

Fig. 7 is a front view of the improved re-

silient cushion used for accurately and comfortably fitting the goggles to the face of the wearer.

Fig. 8 is a top plan view of the same.

Fig. 9 is a plan view similar to Fig. 1, but showing the goggles with the lens retainers removed in order to illustrate the manner in which the lens frames are constructed to increase the user's visual range.

Fig. 10 is an edge elevational view of the parts shown in Fig. 9, portions of the figure being broken away to illustrate the interior construction of the lens positioning means.

Fig. 11 is a vertical sectional view on line 11—11 of Fig. 9.

Fig. 12 is a view similar to Fig. 4 illustrating in elevation a pair of goggles in which the hinge portions secured to the frame of the goggles are made of one piece with said goggles.

Fig. 13 is a sectional view similar to Fig. 5, illustrating another modified lens retainer fastening means, and,

Fig. 14 is a plan view of the fastening means disclosed in Fig. 13.

Goggles of the type referred to and heretofore in use have been subject to the serious defect that the wearer's range of vision in a downward direction is interfered with and limited by reason, not only of the comparatively wide hinge heretofore used for joining the frames together, but also because the frames necessarily utilized in the previous constructions are so shaped that portions thereon project into the line of vision and cut down the range of observation. The said previously known goggles are subject to the further disadvantage that the retainers for the lenses, being riveted to the goggle frames on one of the ends thereof, can be opened to a limited extent only, resulting in difficulty when it is desired to insert the lenses in place, the frames and retainers being subjected to stresses tending to break or bend them when they are spread apart to receive said lenses.

By the peculiar construction of the improved goggles herein described, it is made possible to decrease considerably the horizontal width of the frame and of the lens retainers at the point where the goggles rest

between the eyes of the wearer. It is also possible to remove the positioning means for the lenses substantially out of the line of vision of the wearer, particularly near the nose bridge, thereby practically eliminating the disadvantages and defects above mentioned. The improved structure furthermore makes it possible to insert the lenses into the frames without danger of bending or otherwise stressing the frames or the lenses, and to clamp the lenses and the retainers therefor positively in place, without any danger of accidental displacement of the parts.

In the particular practical embodiment of my invention which is illustrated, the goggles G comprise the symmetrically shaped lens frames 15 and 16, mounted by means of hinge H, to provide respective right and left hand members of said goggles. Secured pivotally by said hinge H to the frames 15 and 16, are the lens retainers C. Between the frames 15 and 16 and retainers C are the lenses L, all held securely in position by the fastener F. The frames 15 and 16 are preferably made of metal, or any material capable of being formed or shaped to be substantially L-shaped in cross-section, and yet provide a device relatively light in weight and highly resistant to deformation.

On the upper side of the goggles G, the frames 15, 16 have a cross-section which is substantially rectangular, as seen at 17. Passing around the ends 18 of the goggles, the angle becomes more obtuse, as viewed at points 19, in order to conform to the contour of the wearer's face. Further, proceeding to the portions which seat upon the cheeks of the wearer, the angle becomes rapidly acute, see portions 20, for a purpose hereinafter appearing. The upright substantially vertical flanges 21 on the frames are curved to provide surface for positioning the goggles on the face of the wearer. The other flanges 22, having the angularities above described, provide the means for positioning the lenses L with respect to the eye E of the wearer, and also provide for increasing the wearer's range of vision as described below.

As shown in Figs. 1, 4 and 9, the portions 23, of flanges 21, intended for disposition about the bridge of the wearer's nose N, are curved concavely outwardly. This formation is necessary since the new hinge construction H brings the inner ends of the goggles so close together that said goggles could not otherwise be fitted properly to the nose of the wearer.

It will be clear from Figs. 1, 2, 9, 10 and 11 that the frames 15 and 16 are curved longitudinally and also transversely from top to bottom as seen in Figs. 2 and 11, to fit the forehead and cheeks. Said transverse curvature is such that the upper portion of the frame, when the latter is worn, will be

arranged considerably forward of and overhang the lower portion of said frame. By this arrangement, when the goggles are worn, the focal center of the lenses L, instead of being in a horizontal line drawn from the center of each lens will be in a line extending upwardly at an angle to the horizontal. This, as shown in Fig. 2, would coincide with the focal center of the eye E.

The portions 20 of the frames 15, 16, particularly approaching the bridge portions 23, are, as previously described, not disposed horizontally or approximately so, but are given a decided inclination downwardly from rear to front, providing sufficient spacing for the arrangement on the frame of the shoulders or lens positioning means 24, which, together with lens retainers C, perform the retaining functions of a bezel. Said shoulders are so mounted as to eliminate interference with the wearer's range of vision as much as is possible and may comprise a member approximately L-shaped in cross-section, one leg 25 thereof being secured to the portions 17, 19, 20 in any suitable manner, as by means of solder or the like, while the other leg 26 is arranged to project away from the leg 25 on the portions 17, 19, 20, at such an angle as to provide a V-shaped groove 27 of suitable size to receive the peripheral portions of the lenses L which generally have bevelled edge portions, as shown, against which the lens retainers C abut.

It will be seen from the drawings that the lenses L do not seat entirely within the V-shaped groove 27. A surface of the lens L, so contacts with shoulder 24, as to constitute a spring bearing for said lens.

As leg 26 approaches the bridge portions 23, its height is materially reduced in order to reduce the amount of material obstructing the wearer's vision in a downward direction. It will be noted (Figs. 2, 9 and 11) that, by reason of the downward inclination of the portions 20 of the frames 15, 16, near the bridge portions 23, grooves of the proper depth and shape are provided between the shoulders 24 and portions 20, even though the upwardly projecting legs 26 are almost entirely removed at these points. Increased removal of material, of course, is preferable in order to increase the range of vision.

In order to further clear the line of vision of obstructions in the vicinity of the bridge, frames 15, 16, are brought together closer than has been possible heretofore by providing the hinge construction H, made up as hereinafter described. Said construction comprises a pair of spaced hinge cylinders 28 on one frame 16, and a single intermediate hinge cylinder 29 on the other frame member. Said cylinders may be formed integral with said frames, as shown in Figs. 3 and 4, or may be secured to said frames in

any other convenient manner as by partially forming some integral with the frames and soldering others thereto. The hinge pintle 30 is passed through said cylinders to align them and retain the frames 15, 16 in operative relation with respect to each other, the cylinder 29 substantially filling the space between the cylinders 28, whereby the frame members are free to swing about the pintle 30 relatively to each other with minimum necessary "play".

Lens retainers C made up in a manner to present a flanged outer periphery shaped to conform to the contour of frames 15, 16 are hingedly mounted on each of said frames and serve to maintain the lenses L removably in place. The ends 31 of the retainers C adjacent the hinge cylinders 28, 29, are provided with a pair of spaced hinged cylinders 32, preferably integral with, and if so desired, formed from the same sheet of material from which the retainers are made. Hinged cylinders 33 for each of said retainers are secured to frames 15, 16, in any suitable manner. Cylinders 33, as seen in Fig. 4, may be individually secured thereto, as by solder or the like. The hinge pin 34 pivotally secures the cylinders 32 and 33, together. It will be seen that, by the hinge construction just described, the retainer C may be rotated freely about pin 34, and as appears from Fig. 3, sufficient space is thereby provided for the quick and easy insertion in place in the groove 27 of the lenses L without bending or straining the parts.

In Fig. 12, is shown a modified hinge construction in which all the hinge cylinders are made integral with the frames or with the lens retainers. On one lens frame 54, the end metal is turned back to form the aligned cylinders 55, 56 between which the cylinder 57 formed similarly on the other frame 58 is received. The metal between cylinders 55, 56 is turned back to form the hinge cylinder 59 which is mounted between the cylinders 60, 61 formed in the same manner on the end of lens retainer 62. On the other lens frames, metal portions on each side of cylinder 57 are turned back to provide the aligned hinge cylinders 63, 64 for receiving the hinge cylinder 65 formed integral with and at the end of, lens retainer 66. Suitable hinge pintles are inserted through the aligned hinge cylinders to position the parts for pivotal movement.

At the ends of the retainers C, opposite to that at which the hinges therefor are located, fastening means F for maintaining said retainers removably, yet securely positioned, on frames 15, 16 are provided. Said lugs include the internally threaded post 35 (Fig. 5) suitably secured to the frame ends 18, as by soldering or riveting. A lug 36 having a perforation 37 therein extends from the retainer C and may be made of a sepa-

rate piece secured to the retainer or may, if desired, be made integral therewith. Said retainers may swing about the hinge pins 34, so that their flanged peripheries overlap the flanged portions 17, 19 and 20 of the frames 15, 16, whereby the lens periphery is covered. In this position perforations 37 register with the threaded openings of the posts 35. A screw 38 is then passed through each perforation 37 and screwed into the post opening, the head 39 of said screw holding the retainer positively, but removably, in place. For attaching the goggles to another article such as a helmet, a strip, or the like, an eye 40 is suitably secured to the post 35 in a suitable opening provided therefor.

In Figs. 6, 13 and 14, are shown modified constructions of the lens retaining locking means. In the modification shown in Fig. 6, a portion 43 is struck up from the vertical flange 21 to provide a prong over which is received the slotted extension 44 of the lens retainer C. The usual snap fastener or bands for attaching the goggles to a helmet or the like, may be secured through the opening thus provided.

In Figs. 13 and 14, a modified fastening means is shown in which a cylinder 45 is secured to the flange 21, said cylinder having an opening 46 therethrough. A pin 47 having a reduced intermediate portion 48 is rotatably positioned in said opening and held against sliding movement by the set screw 49 engaging said reduced portion. The head 50 of said pin has an eye formed therein, for the purpose of receiving a snap fastener or a band or helmet. The extension 51 of the lens retainer C has formed therein the slot 52 through which the head 50 may be passed. Then, by giving the head a half turn, said head and the sides of the slot 52 will act to hold the retainer in locked position.

A cushion 41 of rubber or other suitable resilient and comparatively soft material is shaped to conform to the contour of the rear face of the goggles. Said cushion may be secured to said goggles by stitching, the stitches being received through perforations (not shown) made in frames 15, 16. Said cushion may be interposed between the goggles and the face of the wearer to insure a comfortable air tight and heat tight joint, and also to prevent the discomfort of contacting metallic surfaces and edges, and to insure a proper and comfortable fit to the contour of the face of a wearer, especially on the bridge of the nose and to the cheek portions thereabout. Cushion 41 is thickened and widened at the bridge portion 42 thereof, preferably as shown in Figs. 7 and 8.

The one operation of molding the rubber cushion with a flat surface 53 for contacting the vertical flange 21 and with the thickened

portions 42 avoids the operation of bulging the metal frame at the bridge portions.

If desired, suitable ventilating means 43^a of the Venturi type inducing air circulation in the interior of the goggles and through 5 passages or holes made in the walls of said goggles, may be provided.

It will be seen that there has been provided goggles wherein the obstruction to vision, particularly at and near the bridge of the nose, have been removed to a great degree, that the improved construction provides a positive and secure lug for the lens retainers, and a means for fitting the various 10 wearers, and that the lenses may be quickly 15 and easily inserted thereinto and removed therefrom without undue stressing of the parts.

It will thus be seen that there is provided 20 a device in which the several objects of this invention are achieved, and which is well adapted to meet the conditions of practical use.

As various possible embodiments might be 25 made of the above invention, and as various changes might be made in the embodiment above set forth, it is to be understood that all matter herein set forth or shown in the accompanying drawing is to be interpreted 30 as illustrative and not in a limiting sense.

Having thus described my invention, I claim as new and desire to secure by Letters 5 Patent:-

1. In goggles of the type described, a pair 35 of lens frames of angular cross-section providing an upright flange shaped to fit the face of the wearer, each of said frames having a hinge member extending from said flange at one end thereof, said hinge members extending from their associated frame toward 40 the other frame, and a hinge pin passing through said hinge members for securing said frames directly together.

2. In goggles of the type described, a frame 45 of angular cross-section including an upright flange, and a second flange extending from said upright flange and being inclined downwardly from the rear to the front on the lower portion of said frame, a lens received within 50 each second flange and a shoulder formed on the inner surface of said second flange for abutting said lens.

3. In goggles of the type described, a pair 55 of frames of angular cross-section, each frame including a substantially upright flange adapted to lie adjacent the face of the wearer, and, means for hinging said frames together in close relation, said flange being reduced adjacent said hinging means and being curved 60 concavely outwardly to provide a nose bridge portion for said goggles.

4. In goggles of the type described having a bridge portion, a pair of lens frames of angular cross-section, each including a sub- 65 stantially upright flange arcuately curved

near said bridge portion, and a second flange on the lower sides of said frames inclined downwardly from rear to front at and near said bridge portion, and a hinge for directly hinging said frames together with a minimum 70 distance therebetween.

5. In goggles of the type described having a bridge portion, a frame of angular cross-section including an upright flange, and a second flange extending from said upright flange, a portion of said second flange on the lower side of said frame being inclined downwardly from rear to front at and near said bridge portion, and a shoulder on said frame having a portion thereof extending upwardly. 75 from the inclined portion of said second flange, the upper edge of said portion adjacent the bridge of said goggles being reduced in height to reduce the amount of material obstructing the line of vision at said 80 bridge portion.

6. In goggles of the type described, a lens frame having a bridge portion, said frame being of angular cross-section including an upright flange bent near said bridge portion 85 to provide a space for the reception of the nose of the wearer, and a second flange extending from said upright flange inclined downwardly on the lower side of said frame from rear to front at and near said bridge portion, and lens positioning means on the inclined 90 portion of said second flange.

7. In goggles of the type described, a pair 95 of lens frames of angular cross-section, including an upright flange, each of said frames having a hinge member extending from said flange near the adjacent ends of said frames, and lens retainers having a hinge member integral therewith, and extending therefrom for engaging the hinge members on said 100 frame.

8. In goggles of the type described, a pair 105 of lens frames of angular cross-section consisting of a substantially vertical flange and an inclined flange extending from said first mentioned flange, a shoulder on said inclined flange, a lens retainer hinged to each of said frames near the adjacent ends of the latter, and co-operating means on said retainers and 110 said frames for removably maintaining said retainers in operative engagement with the frames for retaining a lens against said shoulder.

9. In goggles of the character described, a lens frame of angular cross-section having a flange shaped to fit the contour of the face and a second flange extending outwardly therefrom, a lens supported on said second flange and means for abutting said lens, said means comprising a strip secured to and extending 115 upwardly from said second flange at an acute angle thereto and having edge contact with said lens.

10. In goggles of the character described, 120 a lens frame of angular cross-section having

a flange shaped to fit the contour of the face and a second flange extending outwardly therefrom, a lens supported on said second flange and means for abutting said lens, said means comprising a strip secured to and extending upwardly from said second flange at an acute angle thereto and having edge contact with said lens, said strip being gradually reduced in height adjacent the bridge portion of the frame to reduce the amount of material obstructing the line of vision.

In testimony whereof I affix my signature.
KARL KRUENING.
